UNITED STATES PATENT OFFICE.

FELIX C. MONTUORI, OF WASHINGTON, DISTRICT OF COLUMBIA.

DENTAL CASTING MACHINE.

Application filed December 9, 1922. Serial No. 605,952.

To all whom it may concern:

Be it known that I, FELIX C. MONTUORI, a citizen of the United States, residing at Washington, in the District of Columbia, have invented certain new and useful Improvements in Dental Casting Machines, of which the following is a specification.

This invention relates to improvements in mechanism for forming castings particularly inlay castings and cast dentures for restorative work in the oral cavity.

A mechanism of this class generally comprises, in one form or another, a flask (containing the investment material with a mold cavity a sprue or gate duct, and a depression or cavity in the top surface thereof for holding the metal to be melted), a cover or cap adapted to fit tightly upon the top of the flask, a lever for raising and lowering the cover, an air duct for supplying compressed air to the region in the top of the flask, and a valve in the duct adapted to be opened by the backward movement relatively of the support which carries the cap or cover.

One of the objects of the present invention is to provide a simple construction of parts for a mechanism of this class by which the valve can be positively moved from, or to, its closing position, independently of the contact of the cap with the flask, and by which the air under pressure is caused to begin its flow, and its inertia overcome, so that it will be brought to bear upon the molten metal at an instant of time relatively much earlier than is the case with any of the machines within my knowledge.

Fig. 1 is a side elevation of a casting machine embodying my improvements.

Fig. 2 is a perspective view of the air valve.

Fig. 3 is a sectional view of the air valve and adjacent parts.

Fig. 4 is a section longitudinal of part of the lever and handle.

Fig. 5 is a view partly in elevation and partly in section of a modified form of the apparatus.

Fig. 6 is a vertical section of the flask cover and of its vertical moving carriage.

Figs. 7, 8 and 9 show details of the machine in Fig. 5.

Fig. 10 shows in side elevation and section another modification.

Figs. 11 and 12 illustrate in details parts of the mechanism in Fig. 10.

Fig. 13 is a partial section of the base which holds the flask and having a modified yielding flask support.

Fig. 14 is a view, partially in side elevation and partially in vertical section, of another form of dental mold constructed in accordance with the invention and in which a handle controlled poppet valve mechanism is utilized to control the flow of fluid under pressure to the upper portion of the flask, the flask cover being shown in its raised position and with the valve mechanism closed.

Fig. 15 is a view similar to Fig. 14, but showing the flask cover in its lowered position and with the valve mechanism opened to admit fluid under pressure to the upper portion of the flask.

Fig. 16 is an enlarged vertical sectional view through the supporting member or carrier, the flask cover being shown in side elevation.

Fig. 17 is an enlarged fragmentary vertical sectional view through the upper portion of the pedestal or upright and showing the poppet valve mechanism in elevation.

Considering the mechanism illustrated in Figs. 1 to 4; a support or frame-like device is indicated as an entirety by 10. It comprises an upright 11, a base 12, a horizontal arm 12^a and an elongated vertical guide tube 13 preferably all cast integral.

The base part 12 is formed with a cavity or aperture at 14 adapted to permit the seating of a flask such as indicated at 15 containing a mold of the shape desired. The flask may be of any suitable sort; as shown it is adapted to receive the plaster or mold material. 16 indicates the mold cavity, 17 the sprue passage and 18 the usual cavity formed in the upper surface part of the mold material to hold the metal which is to be melted and forced down into the mold cavity 16. The flask may be of either of several sizes such as indicated at 15, 15^a, 15^b, that one being used which corresponds with the size of the casting to be made. 19 indicates the cover or cap which fits upon the top of the flask. This also may be of any suitable sort. As shown in Fig. 3 it is adapted to be moved vertically and is formed with a top part (see Fig. 3), an outer flange 21, and an inner flange 21^a with a packing 21^b for effecting a tight fit with the top of the flask.

The cap 19 is attached to a vertically movable carrier or support 23 through which there is an air passage 24 extending from the bottom to the top. As shown, the carrier or support 23 is tubular and somewhat elongated.

The carrier is arranged to reciprocate in the tube 13 and has at its upper end a plug or closing device 28 adapted to serve as a stop at 27 for the downward movement of the carrier and also adapted to receive the mechanism which introduces the air. This mechanism is indicated, as an entirety by 44 and comprises an inlet duct at 45, a gauge 46, and a control mechanism at 47. The stem 48 is secured in the closing device 28 at the upper end of the carrier 23. 35 indicates a lever which is pivotally mounted at 40 on the upright 11 and is provided with a handle 36. 37 (Figs. 2 and 3) is a valve to control the passage of the air to the cover and flask. The cover is formed with or secured to a short tube or boss 38 which is tightly fitted to the lower end of the carrier 23. In this boss 38 there is an air duct 39 below the valve and air duct 41 above it. The valve has an air passage 37^a and is fitted in a seat formed in the boss 38. The lever 35 is forked, having two leg elements 35^a. In the leg-parts are formed longitudinal slots 43, the slotted parts of the legs lying opposite to the ends of the valve. The valve is caused to rock from the closed position to the open position and back by attachments thereon engaging with the edges of the slots. The attachments shown are flat lugs 49 which may be formed integral with or attached to the valve. They can be made adjustable, angularly, in relation to the valve. When the cover 19 moves toward its uppermost position the valve is rocked by the lever 35 and the lugs 49 so as to close the air duct 41, 39. Shortly after the cover commences to move downward the valve is rocked in the opposite direction by the lever far enough to bring the duct 37^a to the point where it will let air pass through the cover to the flask. Air commences to pass to the cover while the cover is moving down and consequently by the time the cap reaches the top of the flask and is tightly seated thereon, air under pressure in sufficient volume is present at the top of the flask and bearing upon the molten metal. This I found to be a matter of great importance when utilizing metals of the more refractory sort for the castings, such metals quickly lose their melting heat. And with any earlier machines in this class within my knowledge, which had the parts so related, that the air remains cut off from the flask until after the cover makes its entire downward movement and is being pressed tightly against the flask the metal becomes enough cooled so that it

cannot be properly forced through the sprue 65 to the mold cavity.

A relatively considerable period of time elapses between the instant when the heater is withdrawn from the flask to the time when the valve is opened and to the instant 70 when the air pressure is felt by the metal.

A valve actuated directly and positively by the manual motor element for the cap, such as the lever 35, I have found to be much more reliable than those which are 75 actuated by the relatively backward pressure from and movement of the cap, directly or indirectly after it has come into contact with the flask.

The valve and the handle may be made 80 in any suitable way to permit them to be assembled or separated. I prefer to form the lever so that the two side parts 35^a can be separated as indicated by dotted lines in Fig. 4. They can be made of metal sufficiently elastic to permit the separation of the outer ends far enough to allow the inserting or withdrawal of the valve 37 from its seat and to allow the hinging parts at 40 to be separated. The nuts, or bolt and 90 nut at 40^a, 40^b draw the ends of the lever firmly to position at their outer ends as shown in full lines in Fig. 4.

A valve connected to and actuated by the lever can be made and employed in ways 95 other than that shown in Figs. 1 to 4. One modification is shown in Figs. 5 to 8. The stand 50 is formed with a duct 51 in the upright 52. The cover or cap 53 is in this case formed with a top 54 and flanges 55, 56, and 100 a packing 57. The cover is attached to a carrier 58 arranged to slide vertically in the tubular guide 59 on the upright 52. 60 is a small tube positioned axially within the tubular carrier. The carrier tube is closed 105 at the top by a plug 61 through which the tube 60 passes.

The cover has an upwardly projecting tubular boss 62 which is fitted in the lower end of the carrier. The tube 60 is secured 110 by threaded union in the upper end of this boss 62.

A chamber 63 is formed in the boss and 64, 64 are two slot-like apertures extending 115 from the chamber outward.

65 is a pin extending through these slot apertures and across the chamber, 66, 66 are apertures in the side walls of the carrier tube 58 and through these the pin also extends. 67 is the spring positioned in the chamber 120 63. And 68 is a threaded plug seated in the lower part of the boss 62 enclosing the lower end of the chamber 63. The spring 67 bears against this threaded pin and also bears against the underside of the pin, 65. The tension of the spring can be adjusted by the threaded plug 68.

69, 69 are air ducts extending from the

chamber at 64 below the pipe 60 to the lower end of the boss 63.

70 is a lever with handle 71 and pivoted at 73 to an upright 52. The device at 73 which pivots the lever also serves as a rocking valve to control the air passage. The duct 51 in the upright extends from the valve chamber at 73 to the upper end of the upright. 74 is a duct extending down from 10 the valve chamber and communicating with a short tube 75. To the latter tube a flexible tube 76 is connected, the other end of which is joined to the other end of the tube 60. The valve 73 is formed with a port 77 adapted 15 to put the ducts 51 and 74 into communication when the valve is in one position and to cut off such communication when it is in another. It is adjusted so that the air will begin to pass through it at an instant shortly 20 after the commencement of the downward movement of the cap or cover 53.

In this construction (Figs. 5 to 9, inclusive) the valve 73 is formed with laterally extending hubs with journal parts 78. These 25 are seated in apertures in the forked arms 70^a of the lever. 79^a is a bolt or screw for clamping one of the parts 70^a of the lever to one of the journals 78 of the valve. 79^b is a bolt on the opposite side of the valve. Between 30 the bolt head and the adjacent part 70^a of the handle is interposed the spring 80 to provide for adjustment in tension or friction.

The boss 62 on the cover 53 in this construction is fitted somewhat loosely in the lower end of the carrier 58 as shown in Fig. 6. This does not interfere with the air tightness of the duct.

In the apparatus in Fig. 5 the air is conducted 40 from a compressor or tank to the inlet duct 51 through devices at 50^a for controlling and indicating its pressure similar to those at 44 in Fig. 1.

When air is to be admitted to a flask downward movement is imparted to the handle 71 by the lever 70. This moves the cover 53 and shortly after it commences such movement the lever rocks the valve 77 and air is immediately taken from the devices at 50^a 45 through the ducts 51, 76 and 60, to the delivery devices at 69. When the lever 70 is raised the valve is oppositely rotated and cuts off the air between the ducts 51 and 74.

In Figs. 10 to 12 another modified form 55 of mechanism is shown. The stand or frame has the upright 81 with the short vertical duct 82, and base 84 upon which the flask 15^b is shown as supported by means of a holder 15^c. The cap or cover 90 is supported 60 by a vertically moving carrier 88 in the guide 83. At 91 near the lower end of the carrier tube there is an air valve and which is connected to and operated by a lever 92 in the way in which the valve is connected 65 and operated as in the mechanism shown in

Fig. 1. The air introducing and controlling mechanism 85 in Fig. 10 is supported upon the upper end of the standard 81 and communicates with the duct 82. The air from the latter is taken by the connecting tubing 70 87 to a nipple or tube at 89 connecting with the cover support 88.

In Fig. 12 is illustrated the manner of supporting the flask in such way that it can adjust itself in position in case the cap or cover should tend to seat itself upon the top of the flask with even a very slight departure from a perfect fit. The base 84 (in Fig. 12) has a depressed annular plate section at 94 around the aperture 95. Upon this is placed an annulus 96 formed with small V-projections 97 adapted to fit in small V-grooves at 98 in the annular plate 94. 99 is a ring plate which engages, at 100, with the lower ring 96 by means of shallow 85 V-ribs on plate 99 and V-groove on the upper surface of the ring 96. The V-tongues and grooves at 97, 98, and those at 100 are on diameters which are at right angles to each other. Consequently the ring 96 can vibrate 90 for a short distance vertically around a horizontal axis transverse to the base 84 while the ring 99 can vibrate similarly around an axis longitudinal of the base 84. Upon this top ring 99 the supporter 15^c for the flask 95 15^b is placed. It rests upon a thin perforated plate 104 which fits snugly in the cavity in the plate 84. The holder 15^c is centered horizontally by means of a filler ring 103.

It will be understood that a similar filler 100 ring 103 and plate 104 are used when a flask such as that at 15^a is employed. When a large flask such as that at 15^b is in the machine it can be placed directly upon the upper ring 99.

In either case there will be possibility for the flask to yield on any vertical line at its periphery so that it can accommodate itself to the position of the cap or cover. The plate 104 can be supported upon springs, (see 102) 110 Fig. 13. I found that three such springs at 120° apart around the annular plate which surrounds the opening at 95 will be sufficient. As shown in Fig. 13 each of these springs 102 is seated in a recess 101 formed in the annular plate 94^a corresponding to the annular plate 94 in Fig. 12.

In Figs. 14, 15 and 16 there is illustrated a still further embodiment of the invention 120 in which a poppet valve mechanism is employed to control the flow of air to the upper portion of the flask. In this particular construction the device is shown as comprising a base portion 105 which constitutes the support for a flask 106 and which is provided with an upright or pedestal 107. The pedestal 107 is provided with an outwardly and upwardly extending arm 108 which overhangs the flask 106 and which 125 is provided with a vertically extending 130

guide-tube 109 adjacent to its extremity. A substantially tubular carrier or support 110 is slidably mounted within the guide-tube 109 for vertical movement.

- 5 The upper end of the carrier 110 is formed with a substantially hemispherical portion 111 which is provided with an axial aperture 112 extending therethrough. A cylindrical block 113 provided with an axial aperture 114 is secured within the tubular carrier 110, adjacent to the lower extremity thereof, by means of diametrically disposed screws 115 which project through apertures formed in the wall of the carrier. 15 A pipe 116 extends axially through the carrier 110 and is slidably mounted adjacent to its upper and lower ends respectively, in the aperture 112 in the hemispherical portion 111 and in the aperture 114 in the block 113.

20 The lower extremity of the pipe 116 is suitably secured to an upwardly extending boss 117 of a cover or cap member 118. The boss 117 is preferably formed integrally with the cap 118 and is centrally disposed with respect thereto and is adapted to extend within and slidably engage the lower end of the carrier 110. The lower face of the block 113 is recessed as indicated at 119 and forms a seat for a coil spring 120 which encircles the pipe 116 between the block 113 and the upper face of the boss 117. The spring 120 provides for a certain degree of resiliency between the cap 118 and the carrier 110 when the former is brought into operative engagement with the upper portion 25 of the flask 106. A collar 120' is adjustably secured to the upper portion of the pipe 112 and not only prevents the pipe from becoming displaced but limits the amount of relative movement between the cover 118 and the carrier 110. The carrier 110 and its directly associated parts are reciprocated by means of a lever indicated as a whole at 121. This lever comprises a handle portion 122 from which diverge a pair of substantially parallel leg portions 123 which are pivotally connected to each side of the upright 107 as at 124. The leg portions 123 of the lever 121 are each provided with a slot 125 through which the screws 115 are adapted to project for slideable engagement therewith when the carrier 110 and cap member 118 are raised and lowered by means of the handle 122. The pivotal connection 124 between the leg portions 123 and the upright or pedestal 107 preferably comprises a rotatable pivot member 126 which extends transversely through the upright 107 and which is suitably fixed to the extremities of the leg portions 123 to move therewith.

30 The upper portion of the upright 107 is provided with a chamber 127 which is communicably connected with the upper por-

tion of the pipe 116 by means of the flexible tube 128. The chamber 127 is divided into upper and lower compartments 129 and 130 by means of a horizontally disposed wall or partition 131. The upper compartment 129 is normally closed by means of a screw plug 132 which is provided with a centrally disposed aperture 133. A nipple 134 is threaded into this aperture and carries an air control mechanism 135 which is connected to a suitable source of compressed air (not shown) by means of a pipe or tube 136. A pressure gauge 137 is suitably connected to the control mechanism 135 by means of which the pressure in the circuit 75 may be accurately ascertained.

80 The partition 131 is provided with a centrally disposed aperture 138 which may be opened and closed to establish communication between the source of supply of compressed air and the upper portion of the flask 106 by means of a poppet valve 139. This poppet valve 139 is normally maintained in a closed position by means of a coil spring 140 which is interposed between the upper portion thereof and the screw plug 132. The poppet valve 139 is provided with a depending rod or stem 141 which extends downwardly through the aperture 138, chamber 130, through a centrally disposed bore formed in the upright 107 and terminates at a point contiguous to the rotatable pivot member 126. The pivot member 126, adjacent to the point of contact with the lower extremity of the rod 141, is provided with a cam surface 142 which is adapted to be brought to bear against the lower extremity of the rod 141, when the lever 121 is actuated to lower the cover and raises the poppet valve 139 carried thereby against 95 action of the spring 140 to admit air to the upper portion of the flask 106.

100 The length of the rod 141 may be adjusted to compensate for wear to the lower extremity thereof and the cam surface 142 as well as to the valve member 139 and its cooperating valve seat by any suitable means such as the screw and lock nut construction illustrated as a whole at 143 (Fig. 17).

110 The rotatable member 126 is adjustable circumferentially with respect to the operating handle 121 in order to accurately position the cam surface 142 with respect to the lower extremity of the rod 141 so that the opening of the valve 129 will be timed 115 properly with the lowering of the cover 118, as has been emphasized in connection with the other forms of the invention. This can be done by raising or lowering the screw in Fig. 17. In Fig. 7 by loosening the screw 79^a and slightly turning the valve 73 relative to the lever 70, and then tightening said screw again.

120 What I claim is:

- 130 1. The method of making dental castings

with the aid of the pressure of air and the like on the molten metal in a closed mold so that the metal is forced into all parts of the mold, which consists in causing the inertia

5 of the air to be overcome and its flow to the mold to begin before the mold is entirely closed to confine the air.

2. In a metal casting machine of the class described, the combination of a flask containing a mold cavity, a movable cover therefor adapted to close the flask against any substantial escape of air, means for closing and opening said cover relative to the flask, means for supplying fluid pressure within 15 the flask when it is closed and devices cooperating with the cover-actuating means to cause the movement of the compressed air to the flask to begin before said cover has closed the flask.

20 3. In a casting machine of the class described the combination of the vertically movable flask-cover, the stationary upright adapted to support the cover, the air duct in the upright adapted to be put into communication with the space below the cover, the vertically vibratable lever, the valve mounted in the upright for said duct and connected adjustably to the lever and adapted to be moved thereby to its open position 25 while the cover is moving downward.

4. In a casting machine of the class described, the combination of the cover, the carrier for the cover movable vertically therewith and also movable vertically independently thereof, the stationary upright supporting the carrier and having an air duct, the valve in the upright arranged to control said duct and the lever connected adjustably to the valve and arranged to 35 open it while the cover is moving downward.

5. In a metal casting machine of the class described, the combination of a flask containing a mold cavity and narrow sprue leading thereto, a movable cover therefor adapted to close the flask against any substantial escape of air, means for closing and opening said cover relative to the flask, means for supplying fluid pressure within the flask when it is closed and devices cooperating with the cover-actuating means to cause the movement of the compressed air to the flask to begin before said cover has closed the flask.

6. In a metal casting machine of the class described, the combination of a flask containing a mold cavity, a movable cover therefor adapted to close the flask against any substantial escape of air, means for closing and opening said cover relative to the flask, means for supplying fluid pressure within the flask when it is closed, devices cooperating with the cover-actuating means to cause the movement of the compressed air to the flask to begin before said cover has

closed the flask, and adjusting means to 65 regulate the time of beginning of said movement of said air relative to the time of closing of said cover.

7. In a metal casting machine of the class described, the combination of a flask containing a mold cavity, a movable cover therefor adapted to close the flask against any substantial escape of air, a lever for closing and opening said cover relative to the flask, means for supplying fluid pressure within 70 the flask when it is closed, a valve actuated by said lever to cause the movement of the compressed air to the flask to begin before said cover has closed the flask, and means for adjusting said valve to regulate the time 75 of beginning of said movement of said air relative to the time of closing of said cover.

8. In a casting machine of the class described, the combination of a base portion adapted to support a flask, an upright carried by said base portion and having a plurality of compartments formed therein, a carrier slidably mounted on said upright, a cover carried by said carrier for cooperation with said flask, means for communicably connecting one of said compartments with said cover, means for communicably connecting the other of said compartments with a source of fluid under pressure, a poppet valve mechanism for establishing and interrupting communication between said compartments, a lever pivotally connected to said upright for raising and lowering said carrier and said cover and means movable with said lever for opening said valve before said cover is closed on said flask.

9. In a metal casting machine of the class described, the combination of a flask supported by the vertically movable flask cover, the stationary support for the cover, the air duct communicating with the space below the cover, the lever, and the poppet valve mechanism in the stationary support arranged to be moved from its closed to its open position by the lever before the cover is closed on said flask.

10. A dental molding machine comprising a base adapted to support a flask, an upright carried by said base, a cover for said flask movably mounted on said upright, pipes for conducting fluid under pressure through said cover to the upper portion of said flask, a handle for raising and lowering said cover with respect to said flask, a valve mechanism 115 operatively connected to said handle and means for opening the valve before the cover is closed on the flask, whereby the inertia of the fluid in said pipes will be overcome and said fluid will have commenced to flow by the time that said cover engages said flask 120 upon its downward movement.

In testimony whereof I affix my signature.
FELIX C. MONTUORI.
